DEAD-MAN CIRCUIT CONTROL UNIT FOR
TRAIN TRANSFORMERS

William R. Haury, Hamden, Conn., assignor to
The A. C. Gilbert Company, New Haven, Conn.,
a corporation of Maryland

Application May 23, 1951, Serial No. 227,897

16 Claims. (Cl. 336—105)

1

This invention relates to toy electric railroad equipment and particularly to track-side accessories in the nature of a manually operated remote control unit for toy trains.

The appeal of toy railroading to the young mind is influenced by timeliness, that is to say, by the ability of the toy to imitate realistically those characteristics of real railroading which are new and different. In present day railroading the advent of the diesel engine has been of popular interest. Diesel engines have lent impetus to new and different styling of locomotive exteriors. This change of styling has extended to relatively minor units of locomotive equipment such as the throttle control unit handled by the engineer to start, stop and govern the speed of travel of the train.

A characteristic of the modern engineer's throttle which has dramatic significance for the young boy's mind is that popular known as "dead man" control. This is a safety guard against human failure which, in the absence of purposeful pressure by the hand of the operator applied to the throttle control handle, will act automatically to bring the train to a stop.

It is one of the objects of this invention to provide a handle operated, remote control unit for controlling the running of toy electric trains which incorporates the "dead man" function, i. e. to stop the running of the toy train automatically whenever the control handle is released by the hand of the operator.

A further object is to provide auxiliary means for conditioning the "dead man" control handle so that when desired it will not act automatically as aforesaid.

Another object is to enable such control unit, by use of the single control handle thereon, not only to govern the starting and stopping of the toy train, but also to vary the speed of running thereof as desired.

A contributory object is to enable starting and stopping of running of the train to be accomplished whenever desired by mere up and down manual shifting of the single control handle, while the speed of running of the train can be varied as desired by side to side adjustive swinging of the same control handle.

A still further object of the invention is to incorporate in a throttle type of control unit having all of the aforementioned train controlling abilities, structure embodying a shape, proportion and working relationship of parts recognizably similar to comparable parts in the controller of a real diesel locomotive.

2

The foregoing and other objects of the invention will become clear in greater particular from the following description of a successful embodiment thereof having reference to the accompanying drawings wherein:

Fig. 1 is a plan view of a diesel type of control unit embodying the invention.

Fig. 2 is a view taken partly in section on the plane 2—2 in Fig. 1 looking in the direction of the arrows.

Fig. 3 is a fragmentary view of a part of Fig. 1 showing the turret head broken away to expose underlying mechanism.

Fig. 4 is a fragmentary view taken in section on the plane 4—4 in Fig. 3 looking in the direction of the arrows with control handle omitted.

Fig. 5 is a fragmentary view similar to Fig. 2 showing the control handle in a different position.

20 Fig. 6 is a fragmentary view taken in section on the plane 6—6 in Fig. 5 looking in the direction of the arrows.

Fig. 7 is a plan view of the adjustable transformer taken in section on the plane 7—7 in Fig. 5.

Fig. 8 is a view looking in the direction of the arrows from the plane 8—8 in Fig. 5.

Fig. 9 is an enlarged fragmentary view taken in section on the planes 9—9 in Fig. 5 looking in the direction of the arrows.

Fig. 10 is a diagram of circuit connections within the control unit.

The framework of the control unit is designated 12 and includes the top wall of a hollow box-like structure which has an inclined portion 13 serving as an instrument panel. A shallow well 14 in the nature of a circular depression in the top of the box structure has a floor wall 15.

Central of well 14 there is a vertical bearing 17 somewhat elevated above floor wall 15 which guides a plunger shaft 18 and permits rotary and sliding movement thereof. Plunger shaft 18 forms part of a mechanism which operatively couples a manual control handle 19 with a current take-off conductive wheel 20.

The latter rides in an arcuate path across a contactable series of current taps 23 accorded by baring the conductive coils of otherwise insulated transformer secondary wires. The transformer core 24 which carries the transformer windings is stationed on the framework by posts 25 within the control box.

Take-off wheel 20 is rotatably carried at the end of resilient sweep arm 26 in a manner to roll freely along the arcuate path 23 about the

stationary arm pivot 27 that is fixed on and insulated from the transformer core by means of a bar 30 of insulating material. Sweep arm 26 is a thin leaf that normally springs upward into the position shown in Fig. 2 so that take-off wheel 20 tends to be lifted thereby out of contact with the current taps 23 at all points in its arcuate path of swinging movement 23. The outboard or tail end of sweep arm 26 is in permanent electrical connection with a flexible take-off lead 31 which easily trails movements of the sweep arm.

The various movements of sweep arm 26 are brought about by a superimposed resilient leaf type of actuating arm 32. This arm is carried fixedly on the flatted lower end of plunger shaft 18 by means of a hub 34 having a hole correspondingly flatted to tightly fit the shaft. Hub 34 is removably retained on shaft 18 by a split washer 47. Actuating arm 32 is provided with turned down flanges 33 spaced widely enough apart to flank the edges of sweep arm 26 loosely so that bind preventing, free relative sliding movement between the sweep arm and its actuating arm is permitted between flanges 33 and arm 26. Sweep arm 26, however, must follow the swinging movement of the actuating arm 22 at all times and is capable of being depressed, by the superior flexure resisting strength of latter, against its own resilient lifting tendency. Thus sweep arm 26 can be forced downward by actuating arm 32 into the position shown in Fig. 5 wherein the take-off wheel 20 which I prefer to make of carbon rolls across and contacts successively and conductively with the current taps or bared surfaces 23 of the transformer secondary coils in swinging between its extreme positions shown in broken lines in Figs. 7 and 10.

Fig. 5 further shows a broken line position of the control handle 19 wherein the plunger shaft 18, even though permitted to rise to a somewhat higher position than in Fig. 5, is still so positioned that the actuating arm 32 bears downward on sweep arm 26 and maintains conductive contact of take-off wheel 20 with the series of current taps 23. When released by the operator's hand, handle 19 normally will be maintained in a higher position than its broken line position in Fig. 5, namely, in its full line position in Fig. 6, by the axial expanding tendency of a spring coil 36 seated on the floor wall 15 of well 14 and surrounding plunger shaft 18. Natural weight of the operator's hand on handle 19 depresses the latter to its broken line position. Spring 36 in the hollow 38 of turret head 40 constantly presses upward against a thrust washer 37 fixed on plunger shaft 18 by a split retaining ring, but is sufficiently weak to yield to the aforesaid weight of the operator's hand.

Turret head 40 is a rotary body of insulating material molded in the shape of an inverted cup from any suitable plastic insulative material. In effect it serves as a hub for the control handle 19 enabling the latter to be swung from side to side because of the freedom of turret head 40 to swivel with rotary fit on the stationary bearing 17. Handle 19 occupies a diametrical channel 21 in the turret head which latter is held down in well 14 by depending lugs 39 containing threaded holes to receive retaining screws 41. Lugs 39 extend with sliding fit through arcuate slots 42, respectively, in the floor wall 15 of well 14. Plain thrust washers 43 and an axially expansive spring friction washer 29 therebetween are carried between the floor wall 15 and the heads of screws 41.

Removal of screws 41 permits turret head 40 to be removed from the control box.

Turret head 40 causes plunger shaft 18 to turn in unison with it because of the snug but slideable fit on the flatted top end of the latter of a correspondingly shaped hole in the turret head. The extreme upper end of plunger shaft 18 underlies a flat 48 provided on the otherwise round shank 49 of the control handle 19 and is depressible by downward swinging movement of control handle about a hinge pin 44 lodged in the turret head and under which pin the spur end 45 of handle shank 49 is pivotally fulcrumed. This fulcrum construction is such that if shank 49 is manually lifted to a more upright position than shown in full lines in Fig. 2, its fulcrum notch may be disengaged from hinge pin 44 and the entire control handle can thus be removed from the turret head without the use of tools and taken away from the control unit by the operator to prevent unauthorized tampering with the control.

Turret head 40 carries externally a radially projecting spur 50 serving both as a stop and as an index pointer, cooperating in its indicating function with a scale 51 of suitably marked graduations on the framework designating make-believe speed of the train in miles per hour and cooperating in its function as a movement limiting stop with studs 52 placed at each end of the scale of graduations.

In the instrument panel 13 of the box-like framework there are mounted the dials of two instruments, such as a volt meter 53 and an ammeter 54, together with the operating handle 55 of a toggle snap switch. Also visible at the exterior of the control box are the electric bulbs of a red signal lamp 57 and a green signal lamp 58 serving purposes that will appear from the following description of operation.

In Fig. 10 there is diagrammed one system of electric circuits inside the control unit which may incorporate, in addition to the parts already herein described, a primary winding 59 on the transformer and a split secondary winding stemming from the ammeter 54. One branch 56 of the secondary continues directly to a 15 volt binding post 60 of the control unit through the line wire 60 while the other branch of the secondary has a portion bared to provide the current taps 23. The opposite ends of this bared portion connect respectively to an insulated high voltage terminal plate 61 and to an insulated low voltage terminal plate 62. Take-off wheel 20 sweeps from one to the other of these plates in an arc while rolling over and in contact with the current taps 23. The potential derived by the take-off at terminal plate 62 may be some chosen voltage preferably lower than will supply train impelling current to the track of a toy electric railroad while the potential derived by the take-off at terminal plate 61 may be some chosen higher voltage preferably capable of running the train at highest desired speed. The current lead 31 which trails the sweep arm 26 is connected directly to an intermediate binding post 63 of the control unit while the ammeter 54 connects to the base or "no-voltage" binding post 64 of the control unit through the automatic overload protector or circuit breaker 65. The voltage attainable across the binding posts 63, 64 is selectively variable by swinging the sweep arm 26. The red signal lamp 57 is connected in shunt relation to this circuit breaker.

In operation, when handle 19 is partially elevated to its broken line position shown in Figs. 2

and 5, the take-off wheel 20 rides on the current taps 23. By swinging handle 19 counterclockwise from its position shown in Fig. 1, current at maximum volts delivered to the binding post 63 is reduced to less voltage for slowing down the train. The decrease in voltage will continue to a point incapable of running the train after a quarter turn of the handle to its broken line position shown in Fig. 1. Here the take-off wheel 20 will come to rest on the terminal plate 62. the train can be stopped at any time by permitting handle 19 to swing up to full line position in Fig. 2. This occurs automatically as a mere result of releasing the handle from the weight of the operator's hand. Spring 36 then lifts the handle and retracts the actuator 32 upwardly permitting sweep arm 26 to flex upward and lift wheel 20 from engagement with any of the current taps 23. Binding post 60 however is constantly left alive despite the position of take-off wheel 20.

As long as the circuit breaker 65 remains closed it serves to short circuit the red signal lamp 57. The latter therefore remains unlighted normally. The green signal light 58, however, is constantly across the line running to binding posts 60 and 64, respectively, and normally is lighted to indicate that the binding post 60 is alive. Upon occurrence of an overload and consequent breaking of the circuit by the protective circuit breaker 65, the red signal light 57 will glow to indicate trouble until the circuit breaker again closes.

There being possible within the scope of this invention many variations of the exact structures and correlation of parts herein disclosed to illustrate a successful embodiment, the appended claims are directed to and intended to cover all equivalents which fall within the broadest fair interpretation of their terms.

I claim:

1. A handle operated voltage controller automatically operative to break the circuit of its transmitted electric current upon manual release of its voltage controlling handle, comprising in combination with said handle and circuit, a series of successively contactable separately insulated current taps in said circuit, unitary framework carrying said taps, mechanism mounting said handle movably on said framework so as to permit said handle to be swung selectively up and down and from side to side, a current take-off movable in a voltage varying direction to sweep across said taps in contactable relation therewith, and mechanism operatively coupling said handle and said take-off in a manner to convert side-to-side motion of said handle into movement of said take-off in said voltage varying direction and in a manner to convert up and down motion of said handle into movement of said take-off in directions to leave and return into contactable relation to said series of taps.

2. A handle operated voltage controller as defined in claim 1, in which the said mechanism includes a plunger shaft rotatably and slidably guided in the said framework in operable relation to the said handle.

3. A handle operated voltage controller as defined in claim 1, in which the said mechanism includes a turret head mounted to swivel in relation to the said framework, and a plunger shaft coupled in fixed rotative relation to said turret head and longitudinally slidably relatively thereto, said turret head carrying said handle in operative relation to said plunger shaft.

4. A handle operated voltage controller as de-

fined in claim 1, in which the said mechanism includes a turret head mounted to swivel about a vertical axis in relation to the said framework and carrying the said handle mounted thereon in a manner to be swingable upward and downward about a horizontal axis fixed in relation to said turret head and swingable from side to side in unison therewith.

5. A handle operated voltage controller as defined in claim 1, together with a detent positioned to receive and releasably retain the said handle at one extremity of its up and down movement.

6. A handle operated voltage controller as defined in claim 1, in which the said handle includes an elongate arm, together with a spring clip stationed to receive and releasably retain the said handle when swung downward to its lowest position.

7. A handle operated voltage controller as defined in claim 1, in which the said current take-off includes an elongate conductive leaf spring pivotally mounted on the said framework in such position that one end thereof sweeps crosswise the said current taps.

8. A handle operated voltage controller as defined in claim 1, in which the said current take-off includes a spring leaf lever pivotally mounted on the said framework having one of its ends disposed to sweep crosswise the said current taps and its other end conductively connected to and trailed by a flexible current lead.

9. A handle operated voltage controller as defined in claim 1, in which the said take-off includes a conductive flexible leaf spring pivotally mounted to sweep across said current taps and normally biased to separate from all of said taps, and the said mechanism includes an actuating arm swingably coupled to said leaf spring, and a plunger shaft carrying said arm movably mounted on the said framework in a manner to be slidable in unison with said arm in directions toward and away from said leaf spring and to be rotatable in unison with said arm in directions causing said leaf spring to sweep across said current taps.

10. A handle operated voltage controller as defined in claim 1, in which the said mechanism includes a turret head mounted to swivel in relation to the said framework and carrying the said handle pivotally mounted thereon.

11. A handle operated voltage controller as defined in claim 10, together with a detent stationed on the said turret head in a manner to receive and releasably retain the said handle at one extremity of its up and down movement.

12. A handle operated voltage controller automatically operative to break the circuit of its transmitted electric current upon manual release of its voltage controlling handle, comprising in combination with said handle and circuit, a series of successively contactable current taps in said circuit, unitary framework carrying said taps, mechanism mounting said handle movably on said framework so as to permit said handle to be swung selectively up and down and from side to side, a current take-off movable in a voltage varying direction to sweep across said taps in contactable relation therewith, and mechanism operatively coupling said handle and said take-off in a manner to convert side-to-side motion of said handle into movement of said take-off in said voltage varying direction and in a manner to convert up and down motion of said handle into movement of said take-off in directions to leave and return into contactable relation to said series of taps.

75 into movement of said take-off in directions to

leave and return into contactable relation to said series of taps, said mechanism including a disconnectable coupling between said handle and said take-off pivotally anchoring said handle in a manner permitting without the use of tools the removal of said handle from the control unit for preventing unauthorized tampering with the control.

13. A dead-man circuit control unit for toy railroads, comprising in combination, a variable voltage transformer, a case housing said transformer, binding posts on said case, a secondary winding on said transformer, a voltage varying take-off movable in conductive relation to said winding connected to furnish relatively low voltage and relatively high voltage to two of said binding posts respectively, a dead-man handle operatively related to said current take-off comprising an arm movably mounted on said case, and a single handle connected to swing said arm horizontally for varying said take-off voltage and to swing said arm vertically for displacing said take-off from conductive relation to said secondary winding.

14. A dead-man circuit control unit for toy railroads, comprising in combination, a variable voltage transformer, a case housing said transformer, binding posts on said case, a secondary winding on said transformer, a voltage varying take-off movable in conductive relation to said winding connected to furnish relatively low voltage and relatively high voltage to two of said binding posts respectively, a dead-man handle operatively related to said current take-off comprising an arm movably mounted on said case to be swingable horizontally for varying said take-off voltage and to be swingable upward for displacing said take-off from conductive relation to said secondary winding, a spring constantly urging said arm upward, and a detent in the path of downward swinging movement of said arm operative to catch and releasably to hold said arm downward against the upward urge of said spring.

15. A dead-man circuit control unit for toy

5 railroads, comprising in combination, a variable voltage transformer, a case housing said transformer, binding posts on said case, a secondary winding on said transformer, a voltage varying take-off movable in conductive relation to said winding connected to furnish relatively low voltage and relatively high voltage to two of said binding posts respectively, a dead-man handle operatively related to said current take-off comprising an arm movable in selective differing directions for varying said take-off voltage and for displacing said take-off from conductive relation to said secondary winding at will, and a turret head mounted to swivel on said case carrying 10 said arm swingably mounted thereon.

16. A dead-man circuit control unit for toy railroads, comprising in combination, a variable voltage transformer, a case housing said transformer, binding posts on said case, a secondary winding on said transformer, a voltage varying take-off movable in conductive relation to said winding connected to furnish relatively low voltage and relatively high voltage to two of said binding posts respectively, a dead-man handle operatively related to said current take-off comprising an elongate arm, together with structure mounting said arm movably on said case comprising motion transmitting elements assembled to function as a universal joint, whereby said arm can at will be swung simultaneously in a plurality of planes of movement.
